UNITED STATES PATENT OFFICE.

EMIL J. KRAFT, OF RACINE, WISCONSIN, ASSIGNOR TO AJAX RUBBER COMPANY, INC.,
OF NEW YORK, N. Y., A CORPORATION OF NEW YORK.

DESIGN FOR A TIRE.

51,994.

Specification for Design.

Patented Apr. 30, 1918.

Application filed February 21, 1918. Serial No. 218,589. Term of patent 14 years.

To all whom it may concern:

Be it known that I, EMIL J. KRAFT, a citizen of the United States, residing at Racine, in the county of Racine and State of Wisconsin, have invented a new, original, and ornamental Design for Tires, of which the following is a specification, reference being had to the accompanying drawing, forming a part thereof, in which the figure is a plan

view of a section of a tire showing the design.

I claim:

The ornamental design for a tire, as shown.

EMIL J. KRAFT.

Witnesses:

W. P. RITTER,
W. E. LOOMIS.
